Primary Examiner — Darlington Ly(74) *Attorney, Agent, or Firm* — GTC Law Group PC & Affiliates(57) **CLAIM**

The ornamental design for a torque arm, as shown and described.

DESCRIPTION

FIG. 1 is a rear and left side perspective view of a torque arm depicted attached to an electrically powered wheel and frame of a vehicle;

FIG. 2 is an enlarged front and left side perspective view of the torque arm in FIG. 1;

FIG. 3 is an enlarged front and left side perspective view of the torque plate component of the torque arm;

FIG. 4 is an enlarged perspective view of the contoured nut of the torque arm; and,

FIG. 5 is an enlarged front and right side perspective view of the torque plate component of the torque arm.

The broken lines showing portions of an electrically powered wheel and vehicle frame are provided for the purpose of illustrating environmental structure and forms no part of the claimed design.

1 Claim, 3 Drawing Sheets(56)
